US00D845941S

(12) United States Design Patent (10) Patent No.: US D845,941 S
Chen (45) Date of Patent: * Apr. 16, 2019

(54) PROTECTION CASE FOR MOBILE PHONE

(71) Applicant: Jinxin Sang, Shenzhen, Guangdong (CN)

(72) Inventor: Jiadi Chen, Fujian (CN)

(73) Assignee: Jinxin Sang, Shenzhen (CN)

() Term: 15 Years

(21) Appl. No.: 29/590,183

(22) Filed: Jan. 9, 2017

(30) Foreign Application Priority Data

Jul. 11, 2016 (CN) 2016 3 0314591

(51) LOC (11) Cl. 14-03

(52) U.S. Cl.

USPC D14/250

(58) Field of Classification Search

USPC ..... D3/201, 218, 226, 227, 247, 249, 250, D3/269, 303; D13/103, 107, 108, 119; D14/137, 138 R, 138 AA, 138 C, 138 G, D14/203.3–203.7, 217, 238.1, 247, 248, D14/250–253, 440, 447
